US0D1067388S

(12) **United States Design Patent** (10) **Patent No.:** **US D1,067,388 S**
(45) **Date of Patent:** **** Mar. 18, 2025**

(54) **PART**

(71) **Applicant:** **TIANJIN HOMAXLIFE IMP. AND EXP. CO., LTD**, Tianjin (CN)

(72) **Inventor:** **Xiaohua Wang**, Shaoyang (CN)

(73) **Assignee:** **TIANJIN HOMAXLIFE IMP. AND EXP. CO., LTD**, Tianjin (CN)

(**) **Term:** **15 Years**

(21) **Appl. No.:** **29/952,191**

(22) **Filed:** **Jul. 15, 2024**

(51) **LOC (15) Cl.** **08-08**

(52) **U.S. Cl.**

USPC **D8/382**; D8/381

(58) **Field of Classification Search**

USPC D23/205–206, 213, 243, 249, 255, D23/259–261, 263, 266, 269, 303, 358, D23/363, 202, 207–208, 233, 235–238, D23/267–268; D8/2, 78, 321, 332, D8/398–399, 381–383, 400, 403; D24/129; D15/28, 118, 123, 138, 146, D15/199; D6/301, 313, 325, 328, 545, D6/682.3, 683, 702, 512, 547, 648.1, D6/653.18, 654.11, 655.11, 655.18, 6, 83, D6/688.15, 696.3, 706, 710, 718, 718.11; D14/432

CPC F16L 21/08; F16B 2/241; F16B 7/182; F16B 7/042; F16B 7/0426; E03C 1/264; E03C 1/282; E03F 1/006; E03F 3/00; E03F 9/00; E03F 1/007; E03F 5/042; E03F 5/105; E03F 7/04; E03F 5/106; F16K 1/465; F16K 51/02; F16J 13/00; F04D 29/08

(57) **CLAIM**

The ornamental design for a part, as shown and described.

DESCRIPTION

FIG. 1 is a front perspective view of a part, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
